UNITED STATES PATENT OFFICE.

JULIUS DREYFUSS, OF NEW YORK, N. Y.

DESIGN FOR DRESS TRIMMING.

SPECIFICATION forming part of Design No. 22,672, dated August 8, 1893.

Application filed June 10, 1893. Serial No. 477,243. Term of patent 3½ years.

To all whom it may concern:

Be it known that I, JULIUS DREYFUSS, a citizen of the United States, residing at New York city, in the county and State of New York, have invented and produced a new and original Design for Dress-Trimmings, of which the following is a specification, reference being had to the accompanying drawing, forming a part thereof, which represents a plan view of a dress trimming embodying the features of my design.

The design consists of cord figures arranged at each side of a central band figure A, the cord figures appearing connected at

each side of the band figure by transverse cord figures arranged with return effect; and the longitudinal cord figures adjacent to the band figure are united by groupings of transverse cord figures, the band figure appearing between the groups. The band figure appears as solid or unbroken.

I claim—

The design for a dress trimming, substantially as herein shown and described.

JULIUS DREYFUSS.
